UNITED STATES PATENT OFFICE.

WARNER, R. BUXTON, OF LONGMEADOW, MASSACHUSETTS, ASSIGNOR TO BUXTON, INCORPORATED, OF SPRINGFIELD, MASSACHUSETTS, A CORPORATION OF MASSACHUSETTS.

CASE FOR KEYS AND THE LIKE.

Application filed January 5, 1922. Serial No. 527,112.

To all whom it may concern:

Be it known that I, WARNER R. BUXTON, a citizen of the United States, residing at Longmeadow, in the county of Hampden and State of Massachusetts, have invented new and useful Improvements in Cases for Keys and the like, of which the following is a specification.

This invention relates to improvements in cases for keys and the like and, more particularly, to such cases wherein the keys are supported in snap hooks and these hooks are pivotally supported from the case and arranged to swing out of the case along a substantially definite arc-like path. One example of the general type of key case, with which this invention is concerned, is shown in U. S. Letters Patent No. 1,261,692, granted to me on April 2, 1918.

The broad object of this invention is to provide in a key case of the type described means whereby the key-supporting snap hooks may not only swing in the desired arc-like path into and out of the case, but may also turn about an axis substantially at right angles to that about which they swing.

According to this feature of the invention, the hooks are virtually swivelled, as well as pivoted, and can turn with the key when the latter is turned in the lock. Ordinarily, the case is held in the palm of the hand with two or three fingers while the key is held between the thumb and first finger and, in turning the key in the lock, a side strain is applied to the snap hook which tends to open it or distort it. Due to this condition, specially constructed hooks have been provided for key cases to prevent the keys from coming off the snap hooks when thus placed under strain. With the provision for the swivelling movement, the hook will turn relatively to the case, under such conditions, and the undesirable side strains usually imposed are avoided. Also the hooks may swivel while enclosed within the case to enable the keys to pack down into small compass.

Another object of the invention is to provide in a key case, a one-piece snap hook, the shank of which has an integral head adapted to be received in a suitable socket in such a way as to enable both swinging and swivelling movements of the hook.

Another object of the invention is to pro-

vide in a key case of the swivelled and swinging hook type, an improved means for receiving the heads on the shanks of the hooks to permit the swivelling as well as the swinging movement.

Other features of the invention will appear in the following description and in the illustrative embodiment of the invention in the accompanying drawings, in which—

Fig. 1 is an elevational view of a key case embodying the invention, the flaps of the case being shown in open position;

Fig. 2 is a similar view of the key case with the flaps closed;

Fig. 3 is an enlarged fragmentary cross-sectional view taken on the line 3—3 of Fig. 1;

Fig. 4 is a sectional view taken on the line 4—4 of Fig. 3; and

Fig. 5 is an enlarged fragmentary top plan view of the key holder.

Referring to these drawings, the case-forming member may be variously constructed as desired, but preferably, as shown, it is substantially like that of my prior patent, such member being preferably formed from a strip of flexible material, such as leather and the like, and having a back 10 and two flaps 11 foldable in overlapping relation over the back. These flaps 11 may be held together in overlapping relation by any suitable means, such as the interengageable male and female fasteners shown at 12 and 13 respectively.

The back 10 is suitably provided along its upper edge with a pivotal support for a series of snap hooks *h*. Preferably, although not necessarily, this support is afforded by a separate member, such as 14, which I also term a key holder and which is adapted to be secured to the back 10 by some suitable means, of which the eyelets 15 are an exemplification. The member 14, preferably of thin sheet metal, is also provided with a series of sockets 16 in which are received suitably formed heads 17 on the upper ends of the shanks 18 of the snap hooks *h*. These heads 17 are arranged to so engage the sockets 16 that the hooks may not only swing relatively to the support 14 in a substantially definite arc-like path, but may also swivel about an axis at right angles to that about which they turn and this swivelling may occur at any of the many positions

which the hooks may assume during this swinging movement.

The head 17 is formed integrally with the shank 18 by bending the upper end thereof upon itself into circular form, forming a part in the nature of an eye, the axis of which is disposed at right angles to the hook shank. The latter, being constructed of metal having an approximately half-round cross-sectional shape and bent in the manner described, produces a head of substantially spherical shape and this head, being received in the sockets 17, permits the hook to swing about the axis of the sockets and to swivel about an axis at right angles thereto.

The sockets 16, in this instance, are formed by apertures in ears or lugs 19 which are struck up from the member 14 and project outwardly therefrom and in right angular relation therewith. A series of pairs of these lugs 19 are provided and the head 17 is received in and between a pair of lugs with the shank 18 extending outwardly therefrom between the lugs. The shank 18, being of substantially half-round cross-section, is greater in width than in thickness and since the lugs 19 must be spaced by a distance less than the width of shank 18, the latter is recessed in its side edges to provide a part 20 of reduced width and of a width approximately commensurate with its thickness. The part 20 is received between the lugs and can turn about the axis of the shank 18 as well as swing about the axis of the sockets 16.

The particular type of socket described is important in that assembly of the hooks therein is facilitated. Each pair of lugs 19, when struck up from the member 14, need not lie exactly in parallel relation but may diverge as shown in connection with the right hand pair of lugs in Fig. 5. The head 17 may then be inserted between the lugs and the latter forced together into the form shown in connection with the left hand pair of lugs shown in Fig. 5.

The hooks *h* may be variously constructed to receive and removably support keys or other similar articles and this invention is independent of the particular style of hook used although the particular form shown in Fig. 3 has been found particularly advantageous and desirable.

The invention has been disclosed herein, in an embodiment at present preferred, for illustrative purposes, but the scope of the invention is defined by the appended claims rather than by the foregoing description.

What I claim is—

60. 1. A key holder, comprising, a support adapted for attachment to a key case and having a series of pairs of flat parallel lugs projecting at right angles therefrom, aligned recesses provided in each pair of lugs, and 65 a plurality of snap hooks, each adapted to

receive a key or the like and each having a head received in the aligned recesses of a pair of said lugs with the shank of the hook located between such lugs, said head being so engaged in said recesses that the hook 70 can swing in an arc-like path about the axis of said recesses and can swivel about an axis at right angles to the last-named axis.

2. A key holder, comprising, a support adapted for attachment to a key case and 75 having a series of pairs of flat parallel lugs struck up therefrom and projecting at right angles therefrom, aligned recesses provided in each pair of lugs, and a plurality of snap hooks, each adapted to receive a key or the 80 like and each having an integral ball-like head received in the aligned recesses of a pair of said lugs with the shank of the hook located between such lugs, said head being so engaged in said recesses that the hook can 85 swing in an arc-like path about the axis of said recesses and can swivel about an axis at right angles to the last-named axis.

3. A key holder, comprising, a support adapted for attachment to a key case and 90 having a series of pairs of flat parallel lugs projecting at right angles therefrom, aligned recesses provided in each pair of lugs, and a plurality of snap hooks, each adapted to receive a key or the like and each having a 95 head received in the aligned recesses of a pair of said lugs with the shank of the hook located between such lugs, said head being so engaged in said recesses that the hook can swing in an arc-like path about the axis of 100 said recesses and can swivel about an axis at right angles to the last-named axis, the width of the shank of each hook being greater than its thickness and the shank having a substantially half-round cross-sectional shape, said head being formed by bending the end of the shank upon itself about an axis at right angles to the shank into circular form, said shank adjacent said head being recessed in its side edges to make its width substantially 105 commensurate with the space between a pair of lugs.

4. A swivelling and swinging hook for key cases and the like, such hook having a portion of approximately half round cross-sectional shape bent into substantially circular form about such a radius that an approximately spherical head is provided for reception in a suitable socket in the key case.

5. A snap hook, the shank of which has 115 approximately the cross-sectional shape of a segment of a circle and has one flat side and an oppositely disposed rounded side, said shank being bent about an axis parallel to the flat side into substantially the form of a 120 circle having a diameter approximately equal to the width of said flat side, whereby a substantially spherical head is provided.

6. A swivelling and swinging hook for key cases and the like, comprising, a member of 125

approximately half round cross-sectional shape having a portion bent into substantially circular form to form an approximately spherical head for reception in a suitable socket in the key case and having recesses in its side edges adjacent said head.

7. A snap hook, the shank of which is of substantially half round cross-sectional shape bent about an axis substantially at right angles thereto into circular form to provide a ball head for reception in a socket in the key case, said shank having recesses in its side edges closely adjacent said ball to form a portion of reduced width and of a width substantially commensurate with the thickness of the shank.

8. A snap hook for key cases and the like, having a shank the width of which is greater than its thickness and having recesses in its side edges at a point closely adjacent one end thereof to provide a portion of reduced width and of a width substantially commensurate with its thickness.

9. A swivelling and swinging hook for key cases and the like, the shank of which has a part for reception within a socket in the key case and is grooved adjacent said part to provide a portion of reduced size to pass out of the socket.

In testimony whereof I have affixed my signature.

WARNER R. BUXTON.
